RETRACTING TYPE THEATER CHAIR

Joseph G. Prosser and Thomas W. Prosser, Pasadena, Calif., assignors to American Seating Company, Grand Rapids, Mich., a corporation of New Jersey

Application June 26, 1946; Serial No. 679,359

5 Claims. (Cl. 155—116)

1

The present invention relates to chairs and more particularly to chairs of the retracting type for use in theaters, auditoriums and the like. This application is a continuation-in-part of our co-pending application Serial No. 679,354, filed June 26, 1946.

The primary objects of the invention are to provide an improved chair of the retracting type wherein the occupant may move the seat rearwardly in order to permit others to pass in front of him without his having to rise from the seat; to provide such a chair having a combination link and roller or link and sliding block mechanism for mounting the chair back and seat, which mechanism insures easy and comfortable forward and rearward movements and which is concealed below the level of the chair seat; to provide such a chair which when retracted occupies a minimum of space in the rear of the chair; to provide such a chair having improved means for mounting on spaced chair-supporting standards; and in general to provide such a retracting chair which is efficient in operation, reasonably economical in manufacture and attractive in appearance.

An illustrative embodiment of the invention is shown in the accompanying drawings, wherein:

Figure 1 is a perspective view of a retracting chair showing the chair seat and back in their normal, forward positions for occupancy;

Figure 2 is a perspective view similar to Figure 1 showing the chair seat and back in their retracted positions;

Figure 3 is a fragmentary front elevational view of the lefthand side of the chair;

Figure 4 is an inside elevational view of the same, certain parts being shown in vertical section taken on line 4—4 of Figure 3, and the parts of the operating mechanism being shown in their forward positions;

Figure 5 is a view similar to Figure 4 with the operating parts being shown in their rearward positions of retraction.

Referring now in detail to these drawings wherein like parts are designated by the same numerals in the several views, the retracting chair there shown is mounted on a frame comprising spaced, upright, chair-supporting standards 1 having inwardly projecting lugs 2 thereon provided with vertical stud-receiving slots 3, mounting members 4 having outwardly turned flanges 5 with depending, threaded studs 6 adapted to fit into the slots 3, nuts 7 threaded on the lower ends of the studs 6, and a transverse

2

bar 8 secured as by welding to the opposite mounting members 4. The frame thus formed is of sturdy and rigid construction. If desired, members 9 of rubber, cork or other resilient material may be interposed between the flanges 5 of the mounting members and the lugs 2 on the standards for absorbing any vibration of the chair during its retracting and returning movements.

The mounting and operating mechanisms on opposite sides of the chair being of like construction, only one side is shown in Figures 3, 4 and 5 hereinafter described. The mounting member 4 has a rearwardly-downwardly inclined guide track or way 10 therein, and a side plate 11 of generally triangular shape slidably bears in the way, this side plate 11 having a sliding block or roller 12 mounted at its lower front corner and movable forwardly and rearwardly in the way 10. A rear supporting link 13 has its lower end pivotally connected to the mounting member 4 and its upper and pivotally connected at 14 to the side plate 11. The side plate is thus supported in the front by the roller 12 in the way 10 and in the rear by the supporting link 13, and by this arrangement the side plate is movable from a forwardly-downwardly inclined position, rearwardly to a substantially vertical position.

A seat carrier 15 is pivotally connected at its rearward end to the lower rear corner of the side plate 11, and is pivotally connected at its forward end to the lower end of a depending supporting arm 16 pivotally connected at 17 to the uppermost extremity of the rear supporting link 13 above the pivotal connection of said supporting link 13 to the side plate 11. The pivotal connection 17 between the supporting link 13 and the supporting arm 16 is an elongated pin which extends through an arcuate slot 18 in the side plate 11, said slot 18 being concentric with the pivotal connection 14 between the side plate and the rear supporting link.

A chair back 19 is mounted on inwardly turned flanges 20 of the side plates 11 on opposite sides of the chair, as by screws 21. The chair seat 22 is provided with seat arms 23 secured to the opposite sides thereof as by means of screws 24, and these seat arms 23 are pivotally connected at 25 to the seat carriers 15 on opposite sides of the chair. The seat 22 is thus movable forwardly and rearwardly with the seat carriers 15, and is also turnable about a horizontal axis so that it may be raised in order to facilitate sweeping under the chair. When in its lowered position of occupancy, the seat is supported forwardly

of its axis of turning movement by means of stops 27 on the seat carriers 15, on which stops the seat arms 23 rest.

It will be seen that when the chair is retracted, the back 19 is moved rearwardly and is simultaneously rotated to a near vertical position, while the seat 22 moves rearwardly in a substantially straight path by reason of the supporting arms 16 which are slightly raised by the supporting links 13 thus maintaining the seat carriers 22 in a substantially horizontal position during the reTRACTING movement. When the chair is returned to its forward position the back is restored to its normal angular inclination and the seat again moves in a substantially straight path. In the extreme forward position of the chair, the rollers 12 seat in depressed roller seats 26 formed in the forward portions of the ways 10 at opposite sides of the chair, and the chair is thus yieldingly locked in its forward position. Slight rearward pressure on the part of the chair occupant is sufficient to overcome this locking action when it is desired to retract the chair. Forward and rearward movements of the chair are stopped by contact of the rollers 12 with stop means comprising the forward and rearward ends respectively of the ways 10.

It will thus be seen that a retracting chair has been provided having a novel combination of links and rollers in which the mounting and operating mechanism is located out of sight below the seat level, and which mechanism is arranged for easy and comfortable forward-rearward movements of the chair, and while but one specific embodiment of the invention has been herein shown and described, it will be understood that certain details of the construction shown may be altered or omitted without departing from the spirit of the invention as the same is defined by the following claims, wherein the word "frame" is to be construed broadly enough to include either a unitary assembly or a pair of spaced chair standards whose only rigid connection is the floor upon which such pair of standards is installed.

We claim:

1. In a chair, a frame having at its opposite sides forwardly-rearwardly extending ways, side plates having means bearing in the ways for forward and rearward movements, supporting links having their lower ends pivotally connected to the frame and their upper ends pivotally connected to the side plates, a chair back mounted on the side plates, seat carriers pivotally connected to the side plates, a chair seat mounted on the seat carriers, a supporting arm depending from a supporting link and connected to the adjacent seat carrier, and stop means for limiting the forward and rearward movements of the side plates.

2. In a chair, a frame having at its opposite sides forwardly-rearwardly extending ways, side plates having rollers bearing in the ways for forward and rearward movements, supporting links having their lower ends pivotally connected to the frame and their upper ends pivotally connected to the side plates, a chair back mounted on the side plates, seat carriers pivotally connected to the side plates, a chair seat mounted on the seat carriers, a supporting arm depending from a supporting link and connected to the adjacent seat carrier, and stop means for limiting the forward and rearward movements of the side plates.

3. In a chair, a frame having at its opposite sides forwardly-rearwardly extending ways, side plates having means bearing in the ways for forward and rearward movements, supporting links having their lower ends pivotally connected to the frame and their upper ends pivotally connected to the side plates, a chair back mounted on the side plates, seat carriers having their rearward ends pivotally connected to the side plates, a chair seat mounted on the seat carriers, supporting arms having their upper ends pivotally connected to the supporting links and their lower ends pivotally connected to the forward ends of the seat carriers, and stop means for limiting the forward and rearward movements of the side plates.

4. In a chair, a frame having at its opposite sides rearwardly-downwardly inclined ways, side plates having rollers at their lower forward corners bearing in said ways for rearward-downward and forward-upward movements, rear supporting links having their lower ends pivotally connected to the frame and their upper ends pivotally connected to the side plates, a chair back mounted on the side plates, seat carriers having their rearward ends pivotally connected to the side plates rearwardly of said rollers and below the pivotal connections of said side plates to the rear supporting links, a chair seat mounted on the seat carriers, supporting arms having their upper ends pivotally connected to the rear supporting links above the pivotal connections of said rear supporting links to the side plates and having their lower ends pivotally connected to the forward ends of the seat carriers, and stop means for limiting the forward and rearward movements of the side plates.

5. In a chair, a frame having at its opposite sides rearwardly-downwardly inclined ways, side plates having rollers at their lower forward corners bearing in said ways for rearward-downward and forward-upward movements, rear supporting links having their lower ends pivotally connected to the frame and their upper ends pivotally connected to the side plates, a chair back mounted on the side plates, seat carriers having their rearward ends pivotally connected to the side plates rearwardly of said rollers and below the pivotal connections of said plates to the rear supporting links, a chair seat mounted on the seat carriers turnably about a horizontal axis, means on the seat carriers for supporting the seat in a lowered position for occupancy, supporting arms having their upper ends pivotally connected to the rear supporting links above the pivotal connections of said rear supporting links to the side plates and having their lower ends pivotally connected to the forward ends of the seat carriers, and stop means for limiting the forward and rearward movements of the side plates.
